(57) **CLAIM**

The ornamental design for the toilet seat lifter, as shown and described.

DESCRIPTION

FIG. 1 is a perspective view of the toilet seat lifter of present invention wherein the toilet seat lifter is in an extended position; and

FIG. 2 is a front view thereof; and

FIG. 3 is a rear view thereof; and

FIG. 4 is a left side view thereof; and

FIG. 5 is right side view thereof; and,

FIG. 6 is a top view of the present invention.

Wherein the broken lines herein illustrate use and environment and do not form a part of the claimed invention.
